GOTTFRIED WESTPHAL, OF GUTTENBERG, NEW JERSEY, ASSIGNOR TO SHAPIRO & ARONSON, INC., OF NEW YORK, N. Y., A CORPORATION OF NEW YORK.

DESIGN FOR AN ARM FOR LIGHTING-FIXTURES.

54,881.

Specification for Design.

Patented Apr. 13, 1920.

Application filed April 30, 1918. Serial No. 231,760. Term of patent 3½ years.

To all whom it may concern:

Be it known that I, GOTTFRIED WESTPHAL, a citizen of the United States, residing at Guttenberg, in the county of Hudson and State of New Jersey, have invented a new, original, and ornamental Design for an Arm for Lighting-Fixtures, of which the following is a specification, reference being had to the accompanying drawing, forming part thereof.

Figure 1 is a perspective side view of an

arm for lighting fixtures, showing my new design.

Fig. 2 is a bottom plan view showing the outline of the entire article, one-half of the surface ornamentation being shown, it being apparent however, that the other one-half is a duplication thereof.

I claim:

The ornamental design for an arm for lighting fixtures, as shown.
